CABLE MOUNTING RING

Ronald O. Gordon, Rolling Meadows, Ill., assignor to
Illinois Tool Works Inc., Chicago, Ill., a corporation of
Delaware

Filed Mar. 20, 1969, Ser. No. 16,352

Term of patent 14 years

Int. Cl. D8—03

U.S. Cl. D8—229

FIG. 1 is a side elevational view of the cable mounting ring;

FIG. 2 is a side elevational view as viewed from the opposite side of FIG. 1;

FIG. 3 is a top plan view thereof and taken along lines 3—3 of FIG. 1;

FIG. 4 is a bottom plan view thereof as taken along lines 4—4 of FIG. 2;

FIG. 5 is an end elevational view thereof as taken along lines 5—5 of FIG. 1;

FIG. 6 is an end elevational view thereof as taken along lines 6—6 of FIG. 2;

FIG. 7 is a side elevational view of a modification of the cable supporting device;

FIG. 8 is a side elevational view as viewed from the side opposite the side view thereof shown in FIG. 7;

FIG. 9 is a top plan view thereof as taken along lines 9—9 of FIG. 7;

FIG. 10 is a bottom plan view thereof as taken along lines 10—10 of FIG. 8;

FIG. 11 is an end elevational view thereof as taken along lines 11—11 of FIG. 7; and

FIG. 12 is an end elevational view thereof as taken along lines 12—12 of FIG. 8.

I claim:

The ornamental design for a cable mounting ring, as shown and described.
